United States Patent Office.

LEON EUGENE CAMERON MOORE AND JAMES SHOCKEY HAMILTON, OF
PITTSTON, PENNSYLVANIA.

Letters Patent No. 101,902, dated April 12, 1870.

IMPROVEMENT IN LAMPS

The Schedule referred to in these Letters Patent and making part of the same.

To all whom it may concern:

Be it known that we, LEON EUGENE CAMERON MOORE and JAMES SHOCKEY HAMILTON, of Pittston, in the county of Luzerne and in the State of Pennsylvania, have invented certain new and useful Improvements in Lamps; and do hereby declare that the following is a full, clear, and exact description thereof, reference being had to the accompanying drawings and to the letters of reference marked thereon making a part of this specification.

The nature of my invention consists in the employment, upon the neck of the lamp, of a band and spring, which secures an absorbent, of any suitable material, to prevent the lamp from becoming oily on its exterior, all as more fully hereinafter set forth.

In order to enable others skilled in the art to which our invention appertains to make and use the same, we will now proceed to describe its construction and operation, referring to the annexed drawings, in which—

Figure 1 is a plan view, and

Figure 2, a side view of a lamp-collar, with our absorber attached thereto.

Figure 3 is a side view of the absorber.

A represents the collar of a lamp, around which collar is placed a strip, *a*, of blotting-paper, felt, or any other material capable of absorbing oil.

The absorber *a* is confined by means of a metal band, *B*, placed around the same, said band being at each end provided with a hook, *b*, upon which are fastened the ends of a spiral spring, *C*. This spring thus connects the two ends of the metal band *B*, and confines the absorber between said band and the collar *A*.

The absorber thus placed prevents the lamp from becoming oily or greasy by the sweating or overflow of the oil, as this is taken up by the absorber.

The band *B* can be readily removed, and the absorber taken out and replaced by another.

Having thus fully described our invention, What we claim as new, and desire to secure by Letters Patent, is—

In combination with a lamp, the employment of an absorbent, *a*, of any suitable material, secured by the clamp or band *B* and a spring, *C*, all substantially as specified.

In testimony that we claim the foregoing, we have hereunto set our hand this 7th day of February, 1870.

LEON EUGENE CAMERON MOORE.
JAMES SHOCKEY HAMILTON.
